UNITED STATES PATENT OFFICE

112,751

DESIGN FOR A COMBINED CONTAINER AND DISPENSER FOR NESTED DISHES OR THE LIKE

Arthur S. Bowes, Chicago, Ill.

Application April 2, 1938, Serial No. 76,249

Term of patent 14 years

To all whom it may concern:

Be it known that I, Arthur S. Bowes, a citizen of the United States residing at 1000 East 48th Street, Chicago, in the county of Cook and State of Illinois, have invented a new, original, and ornamental Design for a Combined Container and Dispenser for Nested Dishes or the like, of which the following is a specification, reference being had to the accompanying drawing, forming part thereof.

Figure 1 is a view in front perspective of a combined container and dispenser for nested dishes or the like showing my new design;

I claim:

The ornamental design for a combined container and dispenser for nested dishes or the like, as shown.

ARTHUR S. BOWES.
